UNITED STATES PATENT OFFICE.

HUGO J. BACHMAN, OF DENVER, COLORADO.

INTERNAL-COMBUSTION ENGINE.

1,087,566.

Specification of Letters Patent. Patented Feb. 17, 1914.

Application filed January 28, 1913. Serial No. 744,687.

To all whom it may concern;

Be it known that I, HUGO J. BACHMAN, a citizen of the United States, residing at Denver, in the county of Denver and State 5 of Colorado, have invented certain new and useful Improvements in Internal-Combustion Engines, of which the following is a specification.

This invention relates to internal combustion engines and its object resides in the provision of an engine of very simple construction in which the valves which control the admission and exhaust of gases to and from the working cylinder are operated 10 from the crank shaft of the engine without the use of springs or other easily deranged devices, and in which all the operative parts are readily accessible for the purpose of repairs, adjustment or lubrication.

20 In proceeding in accordance with my invention I provide an engine preferably of the four-cycle type in which an open-ended cylinder extends axially in parallel relation to the working cylinder with which it is 25 formed integral and with which it is interiorly connected by means of a pair of ports or passages through which the explosive charge and the spent gases are admitted to and exhausted from the working or 30 compression end of the same.

The first-mentioned cylinder is provided with a port which connects with the carbureter or other source of fuel mixture, and two piston-valves are fitted in tandem relation for reciprocation in the same and, by 35 a suitable transmission mechanism are operatively and independently movably connected with the crank shaft of the engine to cover and uncover the admission and exhaust ports at determinate points in the cycle of movements of the working piston.

40 An embodiment of my invention has been illustrated in the accompanying drawings in the various views of which like parts are 45 similarly designated, and in which—

Figure 1 represents a longitudinal section taken through the improved engine. Fig. 2, an elevation of the lower portion of the same looking in the direction of the arrow A, 50 Fig. 1, Fig. 3, a transverse section taken along the line 3—3, Fig. 1, Figs. 4, 5 and 6, sections similar to that shown in Fig. 1 but drawn to a reduced scale to illustrate different positions of the piston and valves at distinctive points in the cycle of movements 55

of the engine which hereinafter will be more fully described.

To simplify the drawings, only the parts which are essential in the operation of the engine have been shown, and the parts of 60 minor importance such as the crank case, shaft bearings and lubrication appliances which are obviously included in an engine of the type to which this invention appertains have been omitted.

65 Referring more specifically to the drawings, the reference numeral 2 designates the working cylinder of the engine which is open at one of its ends for the passage of the trunk piston 3 which is fitted for reciprocation in the cylinder and which by means of a connecting rod 4 is operatively connected with the crank-arm 5 of the crank shaft 6.

70 Formed integral and axially parallel with the cylinder 2 is the open-ended valve-cylinder 7 in which an intake valve 8 and an exhaust valve 9 are movably fitted in tandem relation to each other, the two cylinders being spaced from each other and surrounded by an integral mantle for the provision of a jacket 10 which completely encircles the same and which as usual is provided with a water inlet 12 and an outlet 13.

75 The two cylinders are interiorly connected by means of an intake port 14 and an exhaust port 15 through which the motive fluid is admitted into and discharged from the compression end of the cylinder, and the valve cylinder is furthermore provided with 80 a port 16 which by means of a conduit 17 is connected with the carbureter or other source of combustible mixture.

85 Recesses 18 formed in the interior surface of the valve cylinder in the planes of the orifices of the ports 14 and 15 are in continuous communication with the same, as is best shown in Fig. 3 of the drawings, for the purpose of providing balance chambers which, when the explosion or compression 95 of the fuel mixture takes place in the working end of the cylinder 2, admit the expansive gases and thus equalize their pressure upon the circumferential surfaces of the two valves to prevent their binding in the cylinder in which they have their movement.

100 The valves 8 and 9 which are of the piston type, are operated by the rotation of a shaft 19 which receives its movement from the crank shaft 6 through the instrumen- 110

tality of a pair of gear-wheels 20 and 21 which are proportioned at a ratio of one to two so that the two revolutions of the crank-shaft necessary in the complete cycle of movements of the working-piston are converted into one revolution of the shaft 19.

The rotary movement of the shaft 19 is converted into independent reciprocating movements of the two valves by means of two eccentrics 22 and 23 of equal eccentricities which are placed at right angles to each other and whose rods are articulately connected with the valve rods as at 24 and 25.

15 The rod 26 of the intake-valve is bored longitudinally for the sliding movement of the rod 27 of the other valve within the same, and it is off-set at 28 as shown in Fig. 2, to connect with the respective eccentric, 20 both rods being guided in their longitudinal movement in boxes 29 which are secured on the crank-case or other suitable part of the engine.

15 The exhaust valve 9 consists of a cylindrical shell 30 which is open at its outer end for the passage of the gases discharged from the working cylinder either into the open or into a conduit 31 which is attached at the end of the valve cylinder, as is shown 30 in Fig. 5. The valve has adjacent its closed inner end, a port 32 which when it is at or near the end of its outward stroke, registers with the exhaust port 15 for the transference of the spent gases from the cylinder 2 to the interior of the shell 30, and the valve 35 is preferably formed with an interior shell to provide an air space 33 which insulates its portion which is in sliding contact with the interior surface of the valve-cylinder 40 from the detrimental influence of the heat of the gases passing from the port 32 to and through its open end.

The intake valve consists of an open-ended cylindrical shell 34 which is formed integral with the hollow rod of the same by means of two transverse partitions 35 and 36 the lower one of which extends obliquely to prevent the accumulation of oil in the space or passage between them. The shell 34 is provided in the said space, respectively in adjacency to the two partitions, with ports 37 and 38 which, when the valve is near or at the end of its outward stroke, register simultaneously with the intake port 50 of the cylinder and the port 16 which connects with the carbureter for the supply of combustible fluid to the said cylinder.

55 The portion of the hollow valve rod within the shell 34 is made of larger diameter than the solid rod of the exhaust valve which moves through the same, to provide a space 39 which by means of openings 40 formed in the rod below the lower partition 36, connects with the atmosphere to prevent 60 the formation of a partial vacuum or the

compression of air in the space between the two valves.

Having thus described the mechanical construction of my improved engine, its operation will be readily understood by reference to the views of the drawings which illustrate the different relative positions of the piston and the valves at four distinctive points in the cycle.

Premising that in the position shown in Fig. 1 the cylinder 2 is filled with explosive mixture which, during the preceding stroke, was admitted through the port 14, the piston 3 will during the return stroke compress the said fluid until it has reached its extreme inward point as shown in Fig. 4 when the mixture is fired by the igniter designated by 41 in Fig. 1, and the consequent expansion of the gaseous fuel drives the piston outwardly. During this outward or working stroke of the piston the exhaust valve 9 commences to uncover the port 15 and remains in register with said port, as is shown in Fig. 5, during the remainder of the said stroke and the following inward movement of the piston during which the cylinder is scavenged of the products of combustion of the ignited vaporous charge, while the intake-valve 8 is moved to the position in which its ports 37 and 38 register with the ports 14 and 16, and the exhaust valve again closes the port 15. During the following stroke which is the last of the cycle the intake port remains uncovered sufficiently long to permit the piston to draw in a fresh charge of fuel and when the piston has reached the end of its stroke, as shown in Fig. 1, the intake port is again covered and all the parts are once more in the initial position ready to commence another cycle.

It will be understood that while in the drawings I have shown the engine as being of the upright type, its position has no influence on its effective operation, and while I have shown and described the engine in the best form at present known to me, variations in the construction and relative arrangement of its parts may be resorted to within the scope of my invention as expressed in the following claims.

I claim—

1. In an internal combustion engine, a working-cylinder and a valve-cylinder connected by an intake port and an exhaust port, said valve cylinder having openings for the admission and discharge of motive fluid, a shaft, a piston in the working cylinder having a driving connection therewith, a pair of independently reciprocating valves disposed in tandem relation in the valve cylinder and provided with rods one of which slides longitudinally within the other, and the outer one of which has a passage for establishing a continuous communication

between the space between said valves and the atmosphere, and cranks connected to be rotated by the movement of said shaft, in operative connection with said rods, where-
5 by the valves are moved to respectively es-
tablish communication between said intake
port and said admission opening and be-
tween said exhaust-port and said discharge
opening at determinate points in a cycle of
10 movements of the piston.

2. In an internal combustion engine, a working cylinder and a valve cylinder connected by an intake-port and an exhaust port, said valve cylinder being open at one
15 of its ends for the discharge of motive fluid and having an opening for the admission of fresh motive fluid, a piston in the working cylinder, and independently reciprocating intake and exhaust valves fitted in tandem
20 relation in the valve cylinder to respectively establish communication between said intake port and said admission opening and between said exhaust port and the said open end of the cylinder at determinate points
25 in a cycle of movements of the piston.

3. In an internal combustion engine, a working cylinder and a valve cylinder connected by an intake-port and an exhaust port, said valve cylinder being open at one
30 of its ends for the discharge of motive fluid and having an opening for the admission of fresh motive fluid, a piston in the working cylinder and independently reciprocating intake and exhaust valves fitted in tandem
35 relation in the valve cylinder to respectively establish communication between said intake port and said admission opening and between said exhaust port and the said open end of the cylinder at determinate points
40 in a cycle of movements of the piston, said exhaust valve comprising a hollow cylinder open at one of its ends to communicate with the open end of the cylinder in which it has its movement and having a
45 port for establishing communication between its interior and the said exhaust port when in register therewith.

4. In an internal combustion engine, a working cylinder and a valve cylinder connected by an intake-port and an exhaust port, said valve cylinder being open at one
50 of its ends for the discharge of motive fluid and having an opening for the admission of fresh motive fluid, a piston in the working cylinder and independently reciprocating intake and exhaust valves fitted in tandem
55 relation in the valve cylinder to respectively establish communication between said intake

port and said admission opening and be-
tween said exhaust port and the said open 60 end of the cylinder at determinate points
in a cycle of movements of the piston, said exhaust valve comprising a double-walled hollow cylinder open at one of its ends to communicate with the open end of the cyl-
65 in which it has its movement and having a port for establishing communica-
tion between its interior and the said ex-
haust port when in register therewith.

5. In an internal combustion engine, a 70 working cylinder and a valve cylinder connected by an intake-port and an exhaust port, said valve cylinder being open at one of its ends for the discharge of motive fluid and having an opening for the admission of 75 fresh motive fluid, a piston in the working cylinder, and independently reciprocating intake and exhaust valves fitted in tandem relation in the valve cylinder to respectively establish communication between said intake 80 port and said admission opening and be-
tween said exhaust port and the said open end of the cylinder at determinate points
in a cycle of movements of the piston, said intake valve comprising a cylinder having 85 an interior passage and in the same, two openings adapted to simultaneously register with said intake-port and said admission opening.

6. In an internal combustion engine, a 90 working cylinder and a valve cylinder connected by an intake-port and an exhaust port, said valve cylinder being open at one of its ends for the discharge of motive fluid and having an opening for the admission of 95 fresh motive fluid, a piston in the working cylinder and independently reciprocating intake and exhaust valves fitted in tandem relation in the valve cylinder to respectively establish communication between said intake 100 port and said admission opening and between said exhaust port and the said open end of the cylinder at determinate points
in a cycle of movements of the piston, said intake valve comprising a cylinder having, 105 interiorly, a passage whose bottom slants for the discharge of oil from the same, and in the said passage two openings adapted to simultaneously register with said intake-
port and said admission-opening.

In testimony whereof I have affixed my
signature in presence of two witnesses.
